The ornamental design for a vehicle cross bar as shown and described.

DESCRIPTION

FIG. 1 is a perspective view of a vehicle cross bar showing my new design;

FIG. 2 is another perspective view thereof;

FIG. 3 is a front elevational view thereof;

FIG. 4 is a rear elevational view thereof;

FIG. 5 is an enlarged left side elevational view thereof;

FIG. 6 is an enlarged right side elevational view thereof;

FIG. 7 is a top plan view of FIG. 1;

FIG. 8 is a bottom plan view thereof; and,

FIG. 9 is an enlarged view of portion 9 shown in FIG. 2. The vehicle cross bar is shown with a symbolic break in its length; the dot-dot-dash broken lines thereof and the appearance of any portion of the vehicle cross bar between the break lines form no part of the claimed design. The broken lines in the drawings depict portions of the vehicle cross bar that form no part of the claimed design. The dot-dash broken lines in FIGS. 2 and 9 represent boundaries of the enlarged portion and form no part of the claimed design.
